No. 705,859.

Patented July 29, 1902.

C. NEUENDORFFER & B. WITSCH.

BOOK COVER.

(Application filed Oct. 23, 1901.)

(No Model.)

UNITED STATES PATENT OFFICE.

CARL NEUENDORFFER, OF NEW YORK, AND BERTHA WITSCH, OF BROOKLYN, NEW YORK.

BOOK-COVER.

SPECIFICATION forming part of Letters Patent No. 705,859, dated July 29, 1902.

Application filed October 23, 1901. Serial No. 79,608. (No model.)

To all whom it may concern:

Be it known that we, CARL NEUENDORFFER, residing at Manhattan borough, New York city, and BERTHA WITSCH, residing at Flat-
5 bush, Brooklyn borough, New York city, State of New York, citizens of the United States, have invented certain new and useful Im-
provements in Book-Covers, of which the fol-
lowing is a specification.

10 What to do with the magazines that ac-
cumulate in the house and the preservation
of which is very much desired in the book-
case has led to the production of the herein-
described improvement whereby the paper
15 covers can be easily and quickly substituted
or supplemented by stiff covers separately at-
tached to the bound back of the book and ef-
fecting thereby a strong binding of stiff cov-
ers to the leaves at the bound back. This
20 novel fabric binder device and the novel man-
ner of applying it is illustrated in the accom-
panying drawings, which, in connection with
the following description and the claims ap-
pended thereto, will particularly set out the
25 parts and combination of parts which consti-
tute the invention.

Referring to the drawings, Figure 1 repre-
sents the inner face of the stiff front cover
and the four-leaf-fabric binder device gummed
30 by two of its four leaves to the hinge edge of
the cover and to its fly-leaf, a flap being shown
as an extension of the cloth facing of the
back cover for covering and finishing the
bound back of the book when its stiff covers
35 are attached each by a four-leaf binder, which
is seen in Fig. 8. Fig. 2 shows the inner face
of the back cover and the four-leaf-fabric
binder device gummed to its hinge edge and
to its fly-leaf by two of its four leaves. Fig.
40 3 shows in cross-section the hinge part of the
front cover and the manner of gumming the
bound back of the book thereto by the four-
leaf-fabric binder device, the covering and
finishing flap for the bound back of the book
45 being also shown as an extension of the front
cover. Fig. 4 is a like section of the hinge
part of the back cover, showing its four-leaf-
fabric binder device gummed by two of its
leaves to the stiff cover and its fly-leaf, the

other two leaves serving to fasten the cover 50
to the bound back of the book. Fig. 5 shows
in perspective the parts of the covers as they
are attached to the bound back of the book
by the four-leaf-fabric binders and the flap
extension of the fabric facing of the front 55
cover which, as a finishing part, is bound
over the bound back of the book as in Fig. 6.
Fig. 6 shows in cross-section the parts as they
appear in Fig. 5, showing the finishing-flap
of the front cover gummed or pasted over the 60
bound back and upon the back cover. Fig.
7 shows the corner of the front cover and the
end of the four-leaf binder turned up to show
how two of its leaves are gummed to the fly-
leaf and to the inner face of the front cover. 65
Fig. 8 shows the four-leaf-fabric binder in
perspective, wherein is indicated the gumming
of two sides of each pair of leaves and the
manner in which each pair of leaves is sewed
together. Fig. 9 is a cross-section of the 70
same, the dotted line indicating the connec-
tion of the separate leaf parts.

To prepare a paper-covered book for being
bound with stiff covers by our invention, a
solid foundation for holding the stiff covers 75
is first prepared by pasting a number of the
leaves of each side of the book together at
the bound back and along the unprinted mar-
gin of the sheets, as indicated by the numeral
1 in Figs. 3, 5, and 6, for obviously the first 80
and last leaves of the book would soon tear
from its wire or other binding if forming only
the hinges of the stiff covers. For binding
the stiff covers to this solid leaf-foundation 1
a four-leaf-fabric binder device, Figs. 8 and 85
9, is employed, and it consists of two strips of
fabric, preferably of muslin, of equal length
and width, sewed together mediate of their
width, so that each strip will form a pair of
leaves 2, 3, 4, and 5, each pair abutting at 90
the line of stitching 6, so as to form a hinge
for the covers and for the book.

Referring to Figs. 1 and 2, let 7 be the front
cover and 8 the back cover, both of paper-
board covered on the outer side with a cloth 95
finish and on the inner side with a paper fin-
ish 9 by pasting. To the end leaves of the
book and to the covers beneath the inner side

of the paper finishing, and to each, is gummed a pair of leaves of one of the four-leaf-fabric binder devices.

10 in Figs. 1, 3, and 6 is the end or fly leaf 5 at the front cover, while in Figs. 2 and 4 at the back cover 11 is the end or fly leaf, and 9 is the inside paper finishing, and when the four-leaf-fabric binder device is gummed or pasted, as hereinafter described, to these covers they are complete each in itself to be bound to and to form the complete binding for the bound back of a paper-covered book, as seen in Figs. 1 and 2. In making these covers first let it be the front cover 7. One of 15 the leaves—say 4—of the four-leaf binder is fastened by its gummed side 12, Fig. 8, to the inner face of the paper finishing 10, and this finishing sheet, with its gummed binder-leaf 4, is then pasted over the inner side of the front 20 cover, as shown in Figs. 3 and 6, thus securely fastening the four-leaf-binder device by two of its leaves to the front cover 7. The next step is to fasten the binder-leaf 5, Figs. 2 and 8, which lies under the leaf 2 in Fig. 1, by its 25 gummed side 13 to the binding edge of, the end leaf 10, which forms the front fly-leaf, and this reinforces and completes the fastening of the four-leaf-binder device by the two leaves 4 and 5 of one of its sewed strips to 30 the front cover, leaving the two leaves 2 and 3 of the other sewed strip of the binder device to be fastened to the bound back by their adjacent gummed faces 14 and 15, Figs. 8 and 9.

35 In Figs. 2 and 4 it is seen that a four-leaf-fabric binder device is fastened to the back cover 8 and to the end or fly leaf 11 of the book in the same manner as an identical four-leaf-binder device is fastened to the front 40 cover, leaving the two gummed binder-leaves 2 and 3 to be bound to the bound back of the book, as in Fig. 6.

To bind the book with the covers, the solid pasted foundation-leaves 1 at the back of the 45 book are pressed and firmly set upon the gummed leaf 2 of the front cover, fastening the two together, while the other leaf 3 of the same binder-strip is turned up and pressed and firmly set against the bound back of the 50 book, as in Fig. 3, thus securing the latter to the four-ply binder and to the front cover. The back cover 8, with its separate four-leaf binder, is then placed upon the book with its 55 gummed binder-leaf 2, Figs. 2 and 4, pressed and firmly set upon the solid pasted leaves 1, while the binder-leaf 3 is turned down and firmly pressed with its gummed side 15 over and against the turned-up binder-leaf 3 of the front cover, and which had already been 60 pasted to the bound back of the book, as in Figs. 5 and 6. In this way both stiff covers are fastened to the bound back of the book; but this leaves the bound back itself uncovered and unfinished, as in Fig. 3, and for covering the bound back to complete the binding 65 a flap 16, which is preferably an extension of

the cloth facing of the front cover, is provided and gummed, so that it may be turned up over and against the back and over and upon the back cover of the book and firmly 70 pressed and set, as in Fig. 6, so that it not only reinforces the binding of the book to the covers, but makes a finished binding. The hem 17, Fig. 5, of the cloth facing of the front cover is extended along the edges of the flap 75 when turned over and pasted on the back cover, and to make a neat finish of the corners of the flap the ends of the hem are slit across, so as to give a free end piece 18, which allows it to be drawn in obliquely with a 80 slight lap on the end of the hem, as at 19 in Fig. 5, and thus prevent the corner of the lap from curling up in the use of the book.

Obviously the flap-back binder can be an extension from either cover and is of a width 85 to adapt it for different thicknesses of books or for several magazines bound together.

To prevent puckering in pasting the leaves of the four-leaf binder especially along the back of the book, they may be slit transversely, as seen at 20 in Fig. 8, so that they will be formed into two or more parts, thereby rendering each part in the length easily pressed to a smooth finish.

While the adjacent sides of each pair of 95 the binder-leaves are stated to be gummed, whereby one pair is attached to the cover and the other pair to the book, it will be understood that the other adjacent sides of each pair are not gummed and that these un-gummed sides are between the end or fly-leaves or the paper cover and the leaves of the book, as seen in Figs. 2 and 7, so that the book can be opened freely at the hinge of the covers.

Obviously the gummed surfaces are moistened in applying them, and while a convenient manner is described of doing this first with the front cover the back cover may be first applied to the bound back.

The covers may be flexible and as well as their finishing-facings made of any suitable material, and the device may be gummed to the paper covers of the magazine and not to the fly-leaves or to either.

Looking at Figs. 1 and 2, it will be noted that each cover part is complete in itself and may be sold as articles of manufacture to be applied directly as the front and back covers of a paper-bound magazine, while such application of one of the cover parts forms also the binding for the back proper and renders the paper-bound book thereby a newly-covered article.

We claim—

1. As a new article of manufacture, a binding for paper books and the like, consisting of a front and back having means for flexibly uniting them together, and fabric binders for the front and back each composed of a plurality of united leaves one of which is secured between the cover part and the inner finish-

ing-sheet, another of which is adapted to be secured to a fly-leaf and the other two of which are adapted to be secured to the outer side and the back of the body of the book in

5 the manner substantially as described.

2. A book having a plurality of its leaves at the front and back gummed to form solid parts, a fabric binder at each inner edge of the book-body, said binders being each composed of a plurality of united leaves a pair of which are secured to an inner edge of the book-body, and a cover consisting of a front and back the front of which has a flap extension for securing the cover parts together, 10 and each cover part having an inner finishing-sheet between which and the cover part another leaf of the binder is secured.

3. In combination with a paper-bound book, a front and a back stiff cover part each having 15 a separate gummed fabric-binder strip along its inner edge, and a gummed flap extending from the front cover along the fabric binder,

the said binders uniting the covers to the book at its back edges and the gummed flap uniting the cover parts, covering the binders and 25 forming a binder for the back.

4. In combination with a paper-bound book having a plurality of its leaves gummed together to form a foundation extending from the bound back on each side of the book, a front and a back cover part each having a separate fabric-binder strip fastened to said foundation parts and the front cover part having a gummed flap for covering the binders, uniting the covers and forming a binding for the back. 30 35

In testimony whereof we affix our signatures in presence of two witnesses.
